UNITED STATES PATENT OFFICE.

ALBERT F. BRANDENBURG, OF DAYTON, OHIO, ASSIGNOR OF ONE-HALF TO HARRY E. PALMER, OF DAYTON, OHIO.

PEN-BRUSH.

1,353,625.

Specification of Letters Patent. Patented Sept. 21, 1920.

Application filed September 18, 1919. Serial No. 324,396.

To all whom it may concern:

Be it known that I, ALBERT F. BRANDENBURG, a citizen of the United States, residing at Dayton, in the county of Montgomery and State of Ohio, have invented a new and useful Pen-Brush, of which the following is a specification.

This invention relates to new and useful improvements in fountain pens, and more particularly to pens used by sign painters for painting signs or other articles wherein it is necessary to make relatively large broad lines.

The primary object of the present invention is to provide a pen having means to permit the operator to control the feed of the fluid from the pen, while the pen is in operation.

A still further object of the invention is to provide means for connecting a pen and its point, to permit of an automatic adjustment of the point with relation to its holder.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed without departing from the spirit of the invention.

In the drawing:

Figure 1 illustrates a longitudinal sectional view of a pen constructed in accordance with my invention.

Fig. 2 is a top plan view of the feeder.

Fig. 3 is a transverse sectional view taken on line 6—6 of Fig. 2.

Fig. 4 is a plan view of the spreader used in connection with my invention.

Fig. 5 is a transverse sectional view of the spreader taken on line 5—5 of Fig. 4, and

Fig. 6 is a longitudinal sectional view of the spreader taken on line 6—6 of Fig. 4.

Referring now to the drawings in detail, reference character 5 indicates the holder of the pen, which includes a substantially tubular member formed of any suitable material, but preferably steel or brass.

One end of said member 5 is reduced as at 6, and is provided with annular shoulders 7 to engage the neck 8 of the flexible rubber connecting members 9, for preventing displacement of the connection.

The rubber connection, as shown is substantially cone shaped, to more conveniently fit the hand of the user, the reduced end thereof adapted to receive the rubber tube 10, which in turn forms a seat for the brush or feeder 11.

As shown, the feeder 11 is provided with a longitudinal slot 12 formed in its upper surface, said slot 12 being for the purpose of feeding fluid from the holder to the writing edge of the brush or feeder 11.

The outer edge of the feeder 11 is beveled as at 13 to accommodate the substantially flat spreader 14, having a transversely curved angular end 15, the shank 15' of said spreader being inserted between the tube 10 and the feeder 11 for securing the same within the holder.

It will therefore be seen that the curved portion 15 forms a pocket, with the slot 12 for normally holding a quantity of fluid, at the feeding point.

Secured within the reduced end 6 of the holder, is a rod 16, which has one end thereof secured within the rubber connecting member 9, and supports a sponge 17, which sponge is of a size to substantially close the interior of the rubber connecting member 9.

From the foregoing it will be seen that the sponge 17 becomes saturated with fluid from the handle 5, and a slight pressure on the rubber connecting member 9 compresses the sponge, and forces a quantity of fluid from the feeder 11.

Having thus described my invention, what I claim is:

In combination with a hollow pen handle, and a feeder, a flexible tubular member having connection with ends of the handle and feeder member, a sponge supported within the flexible tubular member and having its surfaces contacting with the inner walls of the flexible tubular member, whereby pressure on the flexible tubular member causes material contained in the sponge to be forced into the feeder.

In testimony that I claim the foregoing as my own, I have hereto affixed my signature in the presence of two witnesses.

ALBERT F. BRANDENBURG.

Witnesses:

CECIL HANCOCK,
Mrs. W. B. SHAFOR.
